July 1, 1836

U. U. C. & C. W. W. of Waterford & Moosupville,
Sellers Patent.

The Schedule referred to in the Seller's Patent and making part of this same, containing a description in the words of the said U. U. C. & C. W. W. of his improvement in the Mill for Grinding Stone and other Substances.

Be it known, that I, Oliver Wiggman of Waterford in the County of Middlesex and State of Massachusetts have made an improvement in the mill for grinding grain and other substances, called "Wiggman's Improved Mill for grinding" which is described as follows, reference being had to the annexed drawings of the same making part of this specification. This machine consists of a suitable frame A of sufficient size and strength to contain and support the machinery hereof, described, upon one side of which is a vertical spindle B, turning horizontally with its team and in a slot in the top cap C let into a bridge tree D, its upper end bearing in a round aperture in the top piece E of the frame, on this spindle is fastened a curved "cover" F, cut into flats, or channels, spirally around its circumference which cover is surrounded by a hollow conical bed G, made in two parts, resting on a flat frame H, supported and regulated by four stones I, passing through the girts of the frame to raise or lower the bed. Around the bottom of the bed is a square cast iron frame K, through which stones I pass horizontally for regulating the bed, so as to vary or diminish the distance between the bed and stones for grinding coarser or finer as required. One or two wrought iron dogs M, pass over the bed and are bolted to the platform for securing the bed stones firmly to the platform, the stones are raised or lowered by an iron screwrod N, passing through the cap and through the end of the bridge tree, the other end of the bridge tree bearing on a bolt or pin on the opposite side of the frame, or a screwrod may be used at each end of the bridge tree for raising it. The stones are to be nearly as broad, from the spindle, into a brick arch, a brick arch, P, on the end of a horizontal shaft Q, and on the other end of which shaft is a driving pulley R, turned by any convenient power, supplied by the machinery to be turned by long and broad by manual power having blocks on the horizontal shaft, connected to the ends of the arches, by connecting rods.

A hopper and other of the usual contrivances are placed on the top of the frame, by which the material to be ground, grain, Peas, Corn, or other substances, before passing to the stones of the mill, and the contrivance made of shaped animal

with projections formed on its circumference, having a square opening in its center which is supplied with the spindle. The hub being cut flat down to the - to admit said breaker & allow it to play round freely. The working and dimensions of the parts of this machine, may be equal to suit circumstances.

What I claim as my invention and which I desire to secure by Letters Patent consists, in the before described machine for grinding Grains and other substances.
